P. NICOLA.

ARTIFICIAL ARM.

APPLICATION FILED AUG. 22, 1917.

Patented Nov. 27, 1917.

UNITED STATES PATENT OFFICE.

PETER NICOLA, OF WILKES-BARRE, PENNSYLVANIA.

ARTIFICIAL ARM.

1,247,710.

Specification of Letters Patent. Patented Nov. 27, 1917.

Application filed August 22, 1917. Serial No. 187,664.

To all whom it may concern:

Be it known that I, PETER NICOLA, a citizen of the United States, residing at Wilkes-Barre, in the county of Luzerne and State of Pennsylvania, have invented a new and useful Artificial Arm, of which the following is a specification.

This invention relates to artificial limbs, one of its objects being to provide reticulated members combined with coiled springs, said springs serving the double function of giving form to the fingers and holding the members of the device in their extended or normal positions, there being finger actuating elements housed within the springs.

A further object is to provide finger actuating means of novel construction.

With the foregoing and other objects in view, which will appear as the description 20 proceeds the invention resides in the combination and arrangement of the parts and in the details of construction hereinafter described and claimed.

In the accompanying drawings the preferred form of the invention has been shown.

In said drawings:

Figure 1 is a side elevation of an artificial arm embodying the present improvements.

Fig. 2 is a horizontal section through the hand portion.

Fig. 3 is a vertical section.

Fig. 4 is a section on line 4-4 Fig. 1.

Referring to the figures by characters of reference 1 designates a band adapted to be secured about the stump of the forearm, this band being provided with side strips 2 secured thereto in any desired manner. Pivots connected to the upper ends of 35 the side strips are additional side strips 3 riveted or otherwise fastened to a band 4 adapted to be secured about the arm above the elbow. The strips 3 are curved at one end and extend beyond their pivotal connections 5 and extending from the free ends of the strips 3 are studs 6 adapted to work within longitudinal slots 7 formed within actuating strips 8.

The side strips 2 extend beyond the band 50 1 and are attached to a metal ring 9 forming the wrist portion of the device, there being top and bottom skeleton plates 10 and 11 projecting from this wrist portion and attached to a transverse end strip 12. Journaled within and extending transversely of the wrist portion 9 is a shaft 13 to which is

secured a ratchet 14 having an integral arm 15. A pawl 16 is pivotally mounted within the upper part of the wrist portion 9 and one end of this pawl normally engages the ratchet 14 while the other end projects outwardly from the wrist portion and constitutes a finger piece as indicated at 17. A cross pin 18 is connected to the arm 15 and the forward ends of the strips 8 are pivotally mounted on this pin. Diverging rods 19 are also pivotally mounted on the pin 18 and are connected to a cross strip 20 movably mounted between the skeleton plates 10 and 11.

Secured to the strip 12 are the finger members of the device, these members being indicated generally at 21, 22, 23 and 24. Each finger member consists of a plate 25 secured to and extending outwardly from the strip 12 and adapted to swing relative thereto, there being a hinge 26 for connecting this plate 25 to the strip 12. Another hinge 27 connects plate 25 to another plate 28 constituting the intermediate member of the finger portion and a third hinge 29 connects plate 28 to a plate 30 constituting the end member of the finger portion. A tapered coiled spring 31 is secured at its large end to the strip 12 and extends throughout the length 35 of the members 25, 28 and 30 and is fastened to them in any manner desired, as by means of a wire wrapped about the said plates 25, 28 and 30 and threaded through the coiled spring 31. A flexible connection 32, which can be formed of catgut is attached to the outer end of the spring 31 and extends loosely through the spring, and through an opening in the strip 12, as shown at 33, and is attached to the cross strip 20. Thus it will be seen that when the strip 20 is drawn toward the wrist portion 9 it will pull on all of the connections 32 and cause the finger portions to flex toward the wrist portion, thus to grasp and hold any article placed in the hand portion of the device. It is to be understood of course that the finger portions can be provided with suitable coverings of fabric or the like as shown at 34 and the skeleton plates 10 and 11 and the wrist portion 9 can likewise be covered.

The thumb portion of the device is made up of a plate 35 extended outwardly from the wrist portion and suitably braced as at 36, and hingedly connected to this plate at 37 is another plate 38 constituting the end portion of the thumb. A flexible element 39

is attached to the end portion 38 and extends downwardly and backwardly to the cross pin 18 so that when the fingers are drawn up the plate 38 will be swung toward the fingers and the hand portion thus caused to completely encircle the grasped article. A bolt 40 is slidable transversely upon the wrist portion 9 and has a manipulating knob 41 working in a slot 42. This bolt is adapted under some conditions, to project under the pawl 16 and hold it out of engagement with the ratchet 14.

It will be understood that when the parts 1 and 4 are swung relative to each other, the free ends of the strips 3 will pull on the strips 8 and the arm 15, thus causing the ratchet 14 to slip under the pawl 16. At the same time the strip 20 will pull, through the connections 32, on the ends of the fingers 20 and cause said fingers to move to closed positions. Likewise the thumb plate 38 will swing toward the fingers. The parts will be locked in this position unless the bolt 40 should first be moved under the pawl 16, in which event the fingers and thumb will move back to their initial positions as soon as the members 1 and 4 are returned to their normal positions. The springs 31 operate normally to hold the fingers and the members 1 and 4 unfolded.

The entire hand portion can be covered with a glove or the like and a suitable covering, not shown, can be arranged on the fore arm.

55. What is claimed is—

1. An artificial limb including relatively movable arm engaging portions, a wrist portion fixedly connected to one of the arm engaging portions, reticulated fingers each including hingedly connected plates and a coiled spring secured to the plates and constituting a finger form, and means extending longitudinally within the coiled springs and operated by the relative movement of the arm engaging portions for flexing the fingers.

2. An artificial limb including relatively movable arm engaging portions, a wrist portion, reticulated fingers each including a coiled spring constituting a finger form and adapted to hold the finger normally extended, and means extending longitudinally within the coiled springs and operated by the relative movement of the arm engaging portions for flexing the fingers.

3. An artificial limb including relatively movable arm engaging portions, a wrist portion, reticulated fingers each including a coiled spring constituting a finger form and adapted to hold the finger normally extended, and means operated by the relative movement of the arm engaging portions for flexing the fingers, said means including a

slidable member, flexible connections between said member and the free ends of the springs, said connections extended loosely through the springs.

4. An artificial limb including a wrist portion, spaced members fixedly connected to the wrist portion, reticulated fingers extending from said members and each including a coiled spring constituting a form and adapted to hold the finger normally extended, a member slidably mounted between the spaced members, flexible connections between said slidable member and the free ends of the springs, said connections extending freely through the springs, and means for shifting the slidable member to flex the fingers.

5. An artificial limb including a wrist portion, a thumb plate connected thereto, a pivoted thumb plate, reticulated fingers each including a coiled spring constituting means for holding the finger normally extended, a slidable member, and flexible connections between the slidable member and the outer ends of the springs and the outer end of the pivoted thumb plate respectively, certain of the connections being extended freely through the springs.

6. An artificial limb including relatively movable members, a wrist portion, reticulated fingers, a strip slidably mounted, a ratchet pivotally mounted, an arm movable with the ratchet for actuating the slidable strip, means operated by the relative movement of the members for rotating the ratchet and shifting the slidable member, a pawl normally engaging the ratchet, means for holding the pawl out of engaging position, and connections between the slidable strip and the reticulated fingers.

7. In an artificial limb a reticulated member including hingedly connected plates and a coiled spring constituting a finger form and connected to the plates and extending throughout the length of the member, said spring being adapted to hold the member normally extended.

8. An artificial limb including a reticulated member formed of hingedly connected plates, a coiled spring connected to the plates and extending throughout the length of the member, said spring constituting a finger form and constituting means for holding the finger normally extended, and a flexible actuating device extending loosely through the spring and attached to the free end thereof.

In testimony that I claim the foregoing as my own, I have hereto affixed my signature in the presence of a witness.

PETER NICOLA.

Witness:

Ivy E. SIMPSON.
